DESIGN FOR A TOY LAMB

Peter Ganine, Los Angeles, Calif.

Application December 29, 1947, Serial No. 143,383

Term of patent 14 years

(Cl. D34—15)

To all whom it may concern:

Be it known that I, Peter Ganine, a citizen of the United States, residing at Los Angeles, in the county of Los Angeles and State of California, have invented a new, original, and ornamental Design for a Toy Lamb, of which the following is a specification, reference being had to the accompanying drawing, forming part thereof, in which:

Fig. 1 is a side elevational view of a toy lamb, showing my new design;

Fig. 2 is a top plan view;

Fig. 3 is a front elevational view; and

Fig. 4 is a rear elevational view thereof.

I claim:

The ornamental design for a toy lamb, as shown.
PETER GANINE.
